UNITED STATES PATENT OFFICE.

JOEL C. PENNINGTON, OF MOORE'S HILL, INDIANA, AND EDWARD J. PENNINGTON, OF CINCINNATI, OHIO.

RECIPROCATING CYLINDER-HEAD FOR PLANING-MACHINES.

SPECIFICATION forming part of Letters Patent No. 244,290, dated July 12, 1881.

Application filed November 12, 1880. (No model.)

To all whom it may concern:

Be it known that we, JOEL C. PENNINGTON, of Moore's Hill, in the State of Indiana, and EDWARD J. PENNINGTON, of Cincinnati, 5 in the county of Hamilton and State of Ohio, have invented a new and useful Improvement in Reciprocating Cylinder-Heads for Planing-Machines, which improvement is fully set forth in the following specification and accompanying drawings, in which—

Figure 1 is a front view of the cylinder-head, shaft, and attachment. Fig. 2 is a face view of the gear-wheels. Fig. 3 is a longitudinal sectional view of the boxing for the shaft, and 15 Fig. 4 a perspective view of the key for the boxing.

It is the design of this invention to construct such a planer that when the knives in the cylinder or head shall become nicked the surface-plane will not be affected thereby.

It is well known to all who are accustomed to operate planers that should the knives be injured from any cause small ribs will appear on the planed surface in proportion to the size 20 of the nick.

The invention also contemplates improvements in planers, whereby rough and cross-grained lumber can be planed smoothly.

The invention consists in so constructing 30 the cylinder-head that it shall have a reciprocating motion, as will be hereinafter more fully set forth.

In the accompanying drawings, A represents a horizontal shaft journaled at C C', having on one end the head B, to which the planer-knives are attached, and on the opposite end a small pinion, D. This pinion is provided on each side with an enlarged disk, D', the object of which will be hereinafter more fully ex- 35 plained.

E represents a large cog-wheel adapted to mesh with the small pinion D. The wheel E is secured obliquely on the shaft F, and since it meshes with the pinion D, between the disks 45 D', a reciprocating motion is imparted to the shaft A whenever the shaft F is rigidly journaled.

The box C' is provided with a transverse slot, G, and at this point the shaft A has a 50 V-shaped annular groove, H.

A key, I, having two limbs, on the inner edges of which are V-shaped tongues to correspond with the V-shaped groove of the shaft A, is placed in the slot G, so that the limbs of the key pass down on opposite sides of the 55 shaft A, thus preventing the shaft A from reciprocating. When the shaft A is thus secured, the shaft F is allowed to reciprocate; but whenever the key I is removed the shaft F is not permitted to reciprocate. 60

In planing smooth-grained lumber the key is employed in box C', if so desired; but when the knives become nicked, or the lumber is cross-grained, the key is removed and the shaft F secured from moving endwise. By this means 65 the shaft A secures two movements, and compels the succeeding knife to cut away the ribs caused by the nicks in the preceding knife.

It has been found that where only one knife is used, or where the nicks in the opposite knives 70 are in the same line or plane, the reciprocal movement thus given prevents a rib from being formed in the planed surface. It is equally as serviceable in cross-grained lumber, planing it smoothly, and at the same time without any 75 apparent increase of power.

It is apparent that any other mechanical appliance can be substituted to give the shaft A this reciprocal movement, and we do not therefore confine ourselves to the form herein 80 shown as essential to the spirit of our invention.

In practice we find that a small motion is required to produce the desired effect, in some instances less than a sixteenth of an inch being 85 necessary; but it is obvious that the end movement in the shaft A will depend largely upon the size of the nick in the knives and on the quality of the lumber to be planed.

We are aware that the employment of a 90 reciprocating motion in a shaft or cylinder-head has been known in the arts, and we do not, therefore, claim this broadly; but it has been found that for the purpose herein named it is impracticable to impart a reciprocating 95 motion at each revolution of the cylinder-head; hence suitable reducing-gearing has been attached in the form of the obliquely-disposed wheel, to cause the cylinder-head to reciprocate once during each fourth or fifth revolu- 100

tion, which in practice is found to produce the only satisfactory results.

Having described our invention, what we claim as new, and desire to secure by Letters 5 Patent, is—

In a planing-machine, the shaft A, having a small pinion, D, which meshes with an enlarged obliquely-disposed cog-wheel, E, as shown, so adapted that a reciprocal motion will be im- 10 parted to the shaft A at each fourth or fifth

revolution, as herein shown, and for the purpose specified.

In testimony that we claim the above we have hereunto set our hands this 10th day of No- 15 vember A.D. 1880, in the presence of witnesses.

JOEL C. PENNINGTON.

EDWARD J. PENNINGTON.
